FLAP SPLITTING MACHINE

Jacob S. Kamborian, West Newton, Mass.

Application June 24, 1941, Serial No. 399,468

25 Claims. (Cl. 12—17)

This invention relates to an improvement in a flap splitting machine by which the heel portion of an outsole is simultaneously buffed and pressed into close contact with the table on which it rests, a flap is split away from the grain side of the sole beginning at the heel, adhesive is applied to the surface of the sole from which the flap has been split, the flap is returned to its normal position and pressed into contact with the surface of the sole, and finally the sole is ejected from the machine, all as hereinafter set forth and claimed.

The primary object of this invention is to provide such a machine which includes a table on which the soles under treatment rest, buffering, splitting and adhesive-supplying instrumentalities and a frame by which said instrumentalities are carried, said frame being reciprocable longitudinally over the table to carry out the various treatments of the sole mentioned above.

Other objects of the invention reside in the details of construction and operation of the various parts and instrumentalities, all as set forth in the following description of one embodiment of the invention and in the accompanying drawings, in which:

Fig. 1 is a top plan view of the machine embodying this invention;

Figs. 2 and 3 are longitudinal sectional views illustrating the relative positions taken when the splitting of the flap has been completed and as the flap is being returned to its normal position in which it is held by adhesive applied to the surface of the sole;

Fig. 4 is a cross-sectional view taken along the lines 4—4 in Fig. 1;

Fig. 5 is a detail view illustrating the control of the adhesive-applying elements; and

Figs. 6, 7, 8 and 9 are sectional views illustrating various positions taken by the sole-supporting table.

The power by which these various instrumentalities are operated is supplied from any suitable source as, for example, an electric motor 30 here shown (Fig. 4) as mounted between the side walls 22 of the machine frame upon a crossplate 23 secured at its ends to vertical flanges 24 on the side walls. The motor 30 drives the various operative elements of the machine in definite relation to each other whereby the soles are subjected to successive operations as follows; first, the heel end of the grain side of the sole is buffed, second, a flap is split from the grain surface of the sole, third, adhesive is applied to the exposed surface of the sole from which the flap was split,

fourth, the flap is pressed back into the position from which it was split and while so pressing it back it is buffed a second time and caused to adhere to the sole proper, and sixth, the completed sole is ejected from the machine.

The motor 30 drives a shaft 31 to which pulleys 32 and 33 are secured. The pulley 32 is connected by a belt or other means, not shown, to a pulley 35 (Fig. 1) mounted upon a stub shaft 36 (Fig. 3) upon which is also mounted a pulley 37 (Fig. 1). The pulley 37 is connected by a belt to a pulley 38 on the shaft 39 (Fig. 4) of the buffering roll. The shafts 36 and 39 are connected by an adjustable link 40 having at its ends sleeve portions 41 and 42 which are coaxial with the respective shafts. By means of link 40 the shafts may be relatively adjusted so as properly to tension the belt. The stub shaft 36 is supported by the main drive shaft 31, being carried by an arm 43 having annular heads 46 and 44 at its upper and lower ends respectively. The annular head 44, which is concentric with shaft 31, is arranged to rock about a fixed hollow boss 45 projecting from the side wall 2 of the frame. The annular head 46 is interposed between the sleeve 41 and the pulley 31. Preferably, as shown, the shaft 36 is stationary and the pulleys 35 and 37 are connected to constitute a unit which turns freely on the shaft 36. The shafts 36 and 39 which are bodily movable longitudinally of the machine are kept at a predetermined although variable distance apart by the link 40. The distance between the axis of the shaft 31 and that of the shaft 36 is constant.

The pulley 33 is connected by a belt or equivalent means 50 (Fig. 1) with a pulley 51 fixed on a shaft 52 (Fig. 2) which, through gearing worm 53 and 54, drives a longitudinally extending shaft 55. The shaft 55 has a beveled gear 56 at its inner end which meshes with a beveled gear 57 on a transverse shaft 58. A crank 60 fixed to one end of shaft 58 imparts motion to a link 62 which connects the crank 60 with an arm 61 fixed to the shaft 59. The shaft 59 turns in a sleeve 63 carried by one of the side walls 22 of the frame. Mounted upon the shaft 52 is a second pulley 65 (Fig. 4) which drives a pulley 67 (Figs. 1 and 4) on a shaft 68 by means of a belt, not shown.

The work-supporting table 75 (Fig. 4) here shown is adapted to receive two soles S (usually the right and left of a pair) as indicated in dotted lines on Fig. 1. The soles S rest upon beds 76 supported by yieldably separated plates 77 and 78, (Fig. 4) base beams 79 and a bottom plate 80

carried by brackets 26' integral with the side members 22 of the frame, each bracket comprising a vertical flange member 25. The bottom plate 80 is secured by screws 31 to the lower edge of the flanges 25, and the forward ends of the flanges are connected by a crossplate 26 (Fig. 3) to form a housing open at top and rear for the table elements. The base beams 79 are secured to the bottom plate 80 by screws 70 or the like, and are spaced from each other and from the flanges 25 to provide a plurality of longitudinally extending parallel channels.

Reciprocable in the channels provided between the base beams 79 and the side flanges 25 are bars 82. Each bar has at its forward end a horizontal socket which receives one end of a spring 83, the other end of said spring bearing against the crossplate 26 and yieldably resisting forward movement of the bar. The rear end of each bar 82 is at all times held in contact with the periphery of a cam disk 84 (Figs. 1 and 3) on the shaft 58 by a spring 83. The contour of the disk 84 is such that, as the shaft rotates, the bar 82 is slowly advanced, thus compressing the spring 83, and is quickly returned to the starting point by the spring 83 (see Fig. 3) when such movement is permitted by the cam.

In the upper surfaces of the bars 82 are formed bevel-ended depressions 85 (Fig. 2) which coact with cam projections 86 upon the under side of the plate 78. The plate 78 is yieldably held down with the projections 86 in contact with the upper surfaces of the bars 82 by suitable spring means. In the illustrated embodiment (see Fig. 4) bolts 87 are secured at their upper ends to the plate 78 and project below the bottom plate 80, and expansion coil springs 88 surround the shanks of the bolts and bear at their ends upon the under surface of the bottom plate 80 and the upper faces of the bolt heads. Upon the advance of the bars 82 by the rotation of the cam disks 84, the projections 86 which normally rest in the depressions 85 (see Fig. 3) move up the bevel ends of the depressions onto the upper edges of the bars. The plate 78 is thereby raised and acts, through springs 89, yieldingly to elevate the plates 77 and beds 76.

A bar 90 (Figs. 4 and 6) mounted in the space between two beams 79 at the longitudinal mid-center of the machine is, like the bars 82, reciprocable and carries a spring 91 in a pocket at its forward end, such spring 91 bearing against the crossplate 26 and yieldably resisting any forward movement of the bar. The bar 90 is advanced by a cam disk 92 (Fig. 1) on the shaft 58, the rear end of the bar being yieldably held by its spring in contact with the periphery of the cam disk 92. The contour of the disk 92 is such that the bar 90 is moved in unison with the bars 82, being slowly advanced as the shaft rotates and then released so that the spring returns it to the starting position. The beds 76 and plates 77 are separated by a partition strip 93 (Fig. 4). The strip 93 enters a groove extending longitudinally of the plate 78 midway between the side edges and is yieldably urged upward by springs 94. The plate 78 is provided with cam projections 95 which normally rest in bevel-ended depressions 96 in the upper edge of the bar 90. At the beginning of the operation the bar 90, which has been moved by the spring 91 into the position shown in Fig. 6 so that the partition strip 93 is raised, is advanced by the cam 92 so that the plate 78 will descend of its own weight and the partition strip 93 be either below the surface of

the table, as shown in Fig. 4, or be depressed against the urge of the springs 94 by the weight of the roller 130 when, as will be set forth below, it operates on the soles.

- 5 In the channels defined by the beams 79 midway between the bar 90 and the bars 82 are mounted bars 100. The bars 100 extend parallel to the bars 82 and 90 and, like such bars, are yieldably moved rearwardly by springs 101 seated in pockets in the forward ends of the bars and bearing against the crossplate 26. The bars 100 are provided in their upper faces with longitudinally extending bevel-ended depressions 102. Each depression comprises a main portion with a base 103 and a shallower rearward extension therefrom with a base 104. The beds 76 and plates 77 and 78 have axially aligned openings which receive vertically reciprocable pins 105 whose heads 106 normally rest in said depressions 102. Cross straps 107 (Figs. 7, 8 and 9) connect corresponding pins. Springs 108 seated in sockets formed in the under side of the plate 78 act upon the heads 106 so as normally to hold them seated in the depressions 102. When, as shown in Fig. 9, the heads 106 rest upon the bases 104, the pins 105 project above the upper faces of the beds and raise the soles resting thereon out of contact with the upper faces of the beds. Preferably such faces are roughened as by the formation of the teeth 109.
- 10 A shaft 110 (Figs. 7, 8 and 9) extends behind the table 75 and over the bars 100 and has a gear 112 fixed at each end. These gears mesh with rack teeth 113 on the bars 100 so that the shaft 110 is rotated in unison with any reciprocation of the bars. Slidable longitudinally of the machine is an ejector member 115 mounted in guides carried by the vertical flanges 25 of the machine. Secured to the under surface of the member 115 are rack bars 116 which mesh with the gears 112 and are rotated thereby.
- 15 The rear ends of the bars 100 are held by the springs 101 in contact with cams 117 mounted on the shaft 58. As shown particularly in Figs. 7, 8 and 9, the cams are so formed that as the shaft rotates the bars are slowly advanced from the position shown in Fig. 7 to that shown in Fig. 9 and then suddenly retracted to the initial position. As the bars are advanced the pins 105
- 20 are raised to lift the soles off the beds 76 and when the bars are retracted the soles are lowered onto the beds and the plate 115 is advanced to eject from the machine the soles which had been previously raised and lowered and were then resting lightly on the beds.
- 25

- 30 While the soles S rest on the table 75 the heels thereof are first buffed, then flaps F' (Fig. 2) extending forwardly from the rear edges of the buffed heels are split from the soles and raised, and finally the flaps are again returned to contact with the soles and removably secured thereto.
- 35 The elements, by which the soles are so treated, are supported upon a frame 120 which includes side walls 121 and crossbars 122, 123 and 124, the bar 123 being here shown as integral with the side walls. The bases 125 of the side walls 121 rest upon the horizontal bracket members 26' of the main frame. Bars 27 secured to the bracket members 26' by screws 28 or other suitable means
- 40 in cooperation with the vertical flanges 25 define tracks in which the bases 125 ride, the adjacent faces of bases and bars being beveled, as shown in Fig. 4, or otherwise so formed that the frame 120 is held against vertical movement.
- 45

- 50 Fixed to the side walls 121 and the crossbar

123 are rearwardly extending rack bars 126 to which the ends of the crossbar 122 are rigidly secured. The teeth of the rack bars 126 mesh with teeth of pinions 127 carried by the rock shaft 64 which is actuated by a segment 128 fixed to the stub shaft 59 and in mesh with one of the pinions 127. The rack bars 126 are held in mesh with the pinions 127 by idler rolls 129 rotatably supported by the side walls 22 of the main frame. Through the mechanism thus described, including the bars 126 and pinions 127, the frame 120 is reciprocated as a unit over the main frame of the machine, relative to the table 75 and to the soles S carried thereby.

At the forward end of the frame 120 is mounted the heel-buffing mechanism. Such mechanism includes a buffering roller 130 keyed to the shaft 39 for rotation therewith, the ends of the shaft 39 being journaled in bearing units 131, 132. The unit 132 includes a tubular extension 133 coaxial with the shaft 39 and which is fixed within the sleeve portion 42 of the link 40. The forward ends of the side walls 121 are connected by a cross-tube 134 which forms a support for a concentric sleeve 135. The sleeve 135 is rockable on the tube and to it are secured the bearing units 131, 132. An idle roll 136 carried by the unit 132 rides on one of the vertical flanges 25 of the main frame and limits the movement of the roller assembly toward the table 75. A horizontally elongate bar 29 (Fig. 4) rests in a slot in the upper edge of the forward part of the flange and constitutes a support for the roll 136 at certain periods in the operation of the machine. A screw 291 (Figs. 2 and 3) engages the forward end of the bar 29 and is operative to adjust the bar forwardly and rearwardly. A bolt 292 (Fig. 4), carried by the flange 25, adjustably retains the bar 29 in desired position. A spring 137 (Figs. 3 and 4), seated in a socket 138 in the part 132, yieldingly urges the roll 136 downwardly toward the upper surface of the table. A screw cap 139 mounted in a boss 140 (Fig. 4) projecting inwardly from one side wall 121 of the frame, receives the upper end of the spring 137 and is operative to regulate the tension of the spring.

The roller 130 is enclosed between side plates 141 also carried by the sleeve 135. A plate 142 carried by the side walls 121 extends over the top of the roller and a hood 143 carried by the crossbar 124 receives the rear portion of the roller. The hood 143 includes an outlet nozzle 144 connected to a hose 145 through which suction is set up as will be described later. The lower forward portions of the cross-tube 134 and sleeve 135 are cut away to form an opening through which rays of light pass from a bulb 146 within the tube. The tube 134 is rotatably supported in the side walls 121 and carries at one end a knurled cap 147 (Fig. 1) by which the tube may be rotated to adjust the size of the light opening. A spring finger 148 (Fig. 1) carried by the bar 27 bears upon the cap 147 and resists any inadvertent rotation thereof.

The means for splitting the flaps F of the soles S is mounted on the frame 120 at the rear of the sole-buffing mechanism just described. Such splitting means includes a cutting blade 150 (Fig. 3) (adjustably secured to the under side of the crossbar 123) and a crossrod 151 supported by the side walls 121. The cutting edge of the blade 150 projects forwardly of the crossbar 123. The rod 151 is mounted between the crossbar 123 and the hood 143. The rod 151 is cylindrical at the ends and includes an eccentric

cylindrical central portion 152 which projects over the cutting edge of the blade 150. Fixed to one end of the rod 151 is a pinion 153 (Fig. 4) which is in mesh with the threaded lower end 5 of a set screw 154 rotatably supported in an ear 155 that projects outwardly from one side wall 121. The rotation of the screw 154 will turn the rod 151 and thus vary the space between the knife 150 and the eccentric portion 152 of the rod 151 thereby to provide a predetermined but 10 optionally variable thickness of the flap F.

After the soles S are ejected from the machine they are subjected to further treatment and in order to hold the flap F intact and to prevent any 15 tearing or other injury thereto means is provided by which the split flap is returned to its original position and temporarily secured in contact with the surface of the sole proper. Preferably adhesive is applied to one or both of the surfaces 20 which are thus brought into contact when the flap is returned to its initial position. In the illustrated embodiment of the invention the adhesive is applied in lines to the surface of the sole and the flaps are returned to their former 25 position under pressure. Such means will now be described in detail.

The adhesive is applied by a plurality of axially movable plungers 160 carried by the crossbar 123. The plungers occupy forwardly and downwardly inclined pockets 161 in the bar and project at their lower ends into relatively large openings 162 in the blade 150 behind the cutting edge thereof. The head 163 of each plunger is normally held spaced from the crossbar 123 by an 35 expansion spring 164.

Formed in the crossbar 123 is a conduit 165 connected by ports 166 with the pockets 161. The conduit 165 is supplied with adhesive from a 40 stationary tank 167 (Fig. 2) mounted upon the main machine frame. Leading from the base of the tank is an outlet passage 168 by which adhesive is fed under pressure to a hose 169 and thence to one end of the conduit 165. A pair of intermeshing gears 170 act as a pump to compel the 45 adhesive to flow through the passage. One gear 170 is carried and rotated by the continuously driven shaft 68. The other gear is mounted upon a freely rotatable shaft. The tank 167 is preferably inclined (see Fig. 2) and in one wall is 50 provided a pocket 171 leading from the interior of the tank and normally closed by a valve 172 yieldably held seated by a spring 173. The other end of the pocket 171 is connected by a hose 174 to the other end of the conduit 165. Thus a 55 continual circulation of the adhesive is established; i. e., from the tank 167 through the passage 168 and hose 169 to the conduit 165, through the conduit and back to the tank through the hose 174 and pocket 171, the valve 172 being 60 raised by the pressure of the flow. A set screw 175 is provided to regulate the tension of the spring 173 and hence the pressure exerted by the adhesive.

The passages 166 leading from the conduit 165 to the pockets 161 are closed by the rods 160 when 65 no supply of adhesive is desired. Needle valves 176 of any well-known type are provided to regulate the amount of adhesive to be supplied to the passages 166 and also to close the passages when the machine is not in use. The lower end of each plunger 160 is faced off so that the end surface is in a plane parallel to the soles. In the lower end of each plunger is formed a passage 177 which leads from one side of the plunger 70 to the center of the base. The inlet end of 75

the passage 177 is normally above and out of register with passage 166.

When the plungers 160 are depressed, the passages 166 and 177 register so that the adhesive flows to the surface of the soles with which the bases of the plungers 160 are in contact.

The adhesive is applied automatically during the retractive travel of the frame 120. Fixed to a rock shaft 178 supported in the crossbar 123 are a plurality of fingers 179 which rest upon the heads 163 of the plungers 160. One end of the shaft 178 projects beyond one of the side walls and to it is secured an arcuate arm 180 (see Fig. 5). A dog 181 is pivotally supported intermediate its ends upon a pin 182 carried by the side wall. One end of the dog 181 bears against the arm 180 and the other end projects downwardly. Fixed upon the bar 27 carried by the main machine frame is an elongate button 183 mounted at one side of bracket 184 fixed to the bar 27. The parts are so positioned that as the frame 120 is retracted, the button 183 will engage the dog 181, the dog 181 will engage the arm 180, the shaft 178 will be rotated thereby and the fingers will depress the plungers into the position shown in Fig. 3 and hold them so depressed as long as the dog 181 is in contact with the button 183.

The treatments of the soles take place during the reciprocation of the frame 120. The limits of travel of the frame 120 may be varied in accordance with the sizes of the soles under treatment to insure that only the heel portion is buffed and split. To provide for this, the crossbar 122 which connects the rack bars 126 to form a rigid unit is connected to the crossbar 123 by a stud 195 having a central fixed nut portion 197 and right and left threaded end portions 196 which engage suitably threaded sockets in the bars 122 and 123. The rotation of the stud 195 will increase or decrease the distance between the bars, depending upon the direction of rotation and thereby vary the initial location of the frame 120. As shown in Fig. 5 the rack bars 126 are connected to the walls 121 by set screws 198 which pass through slots 199 in the bars so that after the frame has been given the desired length by means of the stud 195 the screws 198 are tightened to insure that it remains at that length.

The shafts 58 and 64 are so related that upon each complete rotation of the shaft 58 the frame 120 is advanced and retracted by the shaft 64, and the treatment of one pair of soles S is completed.

The sequence of operations and treatments will now be described, starting with the frame 120 fully retracted (that is to say at the extreme limit of its movement to the left, as viewed in Fig. 2), at which time the table 75 is raised, the partition 93 is raised and the pins 105 are depressed. The soles S are now placed upon the beds 76 of the table 75 at opposite sides of the partition 93 preferably in contact therewith, as indicated in dotted lines on Fig. 1 with the grain surface of the sole uppermost.

As the frame 120 advances the partition 93 is lowered by the advance of the bar 90, and the roller 130 is brought into contact with the soles S. Since as pointed out above the roller 130 and its associated parts are pivotally supported upon the tube 134 and the arm 43 is pivoted on the sleeve 45, the roller 130 will be lowered by the action of gravity into contact with the soles and yieldingly pressed against the sole by the spring 137. The springs 89 on which the beds 76 and plates 77 are supported will yieldingly oppose the downward pressure exerted by the roller and

thus insure close contact between the upper faces of the soles and the roller and also imbed the teeth 109 of the beds into the under faces of the soles and prevent shifting thereof. The roller 130 not only advances over the soles but is rotated (clockwise in Figs. 2 and 4) so that the upper faces of the soles are buffed or scuffed.

As the roller 130 advances and nears the forward or right-hand end of its stroke, as viewed in Fig. 2, the roll 136 rides up into the cam bar 29 and thus positively lifts the roll 130 out of contact with the forepart portion of the sole.

As this preliminary buffing progresses, the edge of the knife 160 engages the rear edge of the sole at a level usually above the center of vertical thickness of the sole, that is to say, nearer to the grain side than to the flesh side of the sole, the rod 151 pressing upon the sole just above the cutting edge of the knife thereby to insure a uniform although optionally variable thickness of the flap which is split from the sole as the knife advances. As the frame 120 reaches its forward limit the splitting of the flap is completed and the bars 82 are retracted by the springs 83 to allow the table 75 to drop to its lower position.

During the succeeding retraction of the frame 120 the dog 181 strikes the button 183 and through the mechanism previously described causes the fingers 179 to advance the plungers 160 into contact with the soles (see Fig. 3). A constant flow of adhesive through the conduit 165 is assured by the pump 170 so that as soon as the passages 166 and 177 are brought in register by the advance of the plungers 160, adhesive flows from the conduit 165 onto the soles. This continues until the dog 181 has passed the button, at which time the plungers 160 are near the heel ends of the soles. As the frame 120 approaches its rearward limit the bars 82 again act to raise the table 75 so that the flaps are pressed down into their original positions on the strips of adhesive by the roller 130. Since as pointed out above the roller 130 is positively rotated, it will act not only to press down the flaps but also to buff the heels of the soles a second time.

When the rod 151 has passed off the soles the bars 100 reach their final position (Fig. 9) so that the pins 105 raise the soles bodily from the beds. Immediately thereafter the bars 100 are snapped back by the springs 101 causing the plate 115 to eject the soles S which are now resting lightly upon the teeth 109. Preferably a suitable collection receptacle (not shown) is so positioned as to receive the soles as they are ejected from the machine. Finally the bar 90 acts to raise the partition 93 so that the sequence just described can be repeated.

While one embodiment of this invention has been shown and described in detail, it will be understood that the invention is not limited thereto and that such embodiment may be modified or other embodiments made without departing from the spirit and scope of the invention as set forth in the following claims.

65 I claim:

1. A machine of the class described comprising a table on which the sole to be treated rests, a frame reciprocable over said table longitudinally of the sole resting thereon, and heel flap splitting, adhesive applying and buffing instrumentalities carried by said frame, said buffing and said flap splitting instrumentalities acting during the travel of the frame in one direction and said adhesive applying instrumentality acting during the travel of the frame in the opposite direction.

2. A machine of the class described designed to treat two soles at the same time, said machine comprising a table of sufficient width to receive a pair of soles with their longitudinal axes substantially parallel and upon which the soles rest while being treated, a vertically movable partition extending longitudinally of the table and constituting positioning means with which the adjacent edges of the two soles may initially contact, a frame reciprocable over said table longitudinally of the sole resting thereon, means carried by said frame to split a flap at the heel portion of each sole during the reciprocation of the frame in one direction, means carried by the frame to apply adhesive to the surface of that portion of the sole from which the flap was split, and means carried by the frame to wipe the flap down upon the adhesive treated surface, said adhesive applying and flap wiping means acting during the reciprocation of the frame in the opposite direction, and means operative to lower the sole positioning partition below the upper surface of the table prior to the commencement of the action of the wiping means.

3. A machine of the class described designed to treat two soles at the same time, said machine comprising a table of sufficient width to receive a pair of soles with their longitudinal axes substantially parallel and upon which the soles rest while being treated, a vertically movable partition extending longitudinally of the table and constituting positioning means with which the adjacent edges of the two soles may initially be engaged, a frame reciprocable over said table longitudinally of the soles resting thereon, means carried by said frame to buff the heel portions of the soles and to split a flap at the heel portion of each sole during the reciprocation of the frame in one direction, and means carried by the frame to apply adhesive to the surface of that portion of the sole from which the flap was split, the frame carrying means operative to wipe the flap down upon the adhesive treated surface, said adhesive applying and flap wiping means acting during the reciprocation of the frame in the opposite direction, and means for raising and lowering said table during the reciprocation of said frame, and means operative to lower the sole positioning partition below the upper surface of the table at a time before the buffing means begins to act.

4. A machine of the class described comprising a table on which the sole to be treated rests, a frame reciprocable over said table longitudinally of the sole resting thereon, a knife by which a flap is split from the heel of the sole and raised above the sole during the travel of the frame in one direction, adhesive applying means including a nozzle, the blade of the knife having an opening through which the nozzle may be projected, means holding the nozzle in elevated inoperative position during the splitting operation, and means for projecting the nozzle down through the opening in the knife blade at the completion of the splitting operation, and means causing adhesive to be applied through said nozzle directly to that surface of the sole from which the flap was split during the travel of the frame in the opposite direction.

5. A machine of the class described comprising a table on which the sole to be treated rests, a frame reciprocable over said table longitudinally of the sole resting thereon, a knife by which a flap is split from the heel of the sole and raised above the sole during the travel of the frame

in one direction, adhesive applying means including a nozzle extending through the blade of the knife, a dog, and means which, during the travel of the frame in the opposite direction, engage said dog and cause adhesive to be applied through said nozzle onto the surface of the heel from which the flap was split.

6. A machine of the class described comprising a table on which the sole to be treated rests, a frame reciprocable over said table longitudinally of the sole resting thereon, a knife by which a flap is split from the heel of the sole and raised above the sole during the travel of the frame in one direction, adhesive applying means including a plurality of transversely spaced retractile nozzles, the blade of the knife having openings through which the several nozzles may be projected, means normally holding the nozzles with their lower ends elevated out of contact with the sole, means operative to project the nozzles downwardly through the knife blade so as to dispose their delivering ends closely adjacent to that surface of the sole from which the flap has been split, means to supply adhesive to the nozzles for delivery by the nozzles to the surface of the sole from which the flap was split during the travel of the frame in the opposite direction, and means for wiping said flap down upon the adhesive treated surface.

7. A machine of the class described comprising a table on which the sole to be treated rests, a frame reciprocable over said table longitudinally of the sole resting thereon, a knife by which a flap is split from the heel of the sole and raised above the sole during the travel of the frame in one direction, adhesive applying means including a nozzle extending through the blade of the knife, means causing adhesive to be applied through said nozzle onto the surface of the heel from which the flap was split during the travel of the frame in the opposite direction, means for wiping said flap down upon the adhesive treated surface, and means for removing said sole from the table.

8. A machine of the class described comprising a table on which the sole to be treated rests, a frame reciprocable over said table longitudinally of the sole resting thereon, a knife by which a flap is split from the heel of the sole and raised above the sole during the travel of the frame in one direction, adhesive applying means including a nozzle extending through the blade of the knife, means causing adhesive to be applied through said nozzle onto the surface of the heel from which the flap was split during the travel of the frame in the opposite direction, means for wiping said flap down upon the adhesive treated surface, and means for removing said sole from the table, said removing means including elements by which the sole is raised and an ejector which acts upon the raised sole.

9. A machine of the class described comprising a table on which the sole to be treated rests, a frame reciprocable over said table longitudinally of the sole resting thereon, a positively rotated buffing roller mounted on said frame which buffs the heel portion only of the sole at the beginning of the travel of the frame in one direction and at the conclusion of the travel of the frame in the opposite direction, and a flap splitting knife by which the heel portion of the sole is split during the travel of the frame in the first-named direction, the flap being wiped down by said roller against the surface from which it was split during the travel of the frame in the second-named direction.

10. Method of preparing a sole comprising buffing the rear portion of the sole, splitting a flap of predetermined thickness from the sole, applying adhesive to that area of the sole from which the flap was split, laying the flap back against the adhesively coated surface of the sole proper and pressing the flap against the adhesively coated surface by the application of buffing means to the grain surface of the flap.

11. A machine of the class described comprising a table on which the sole to be treated rests, a frame reciprocable over said table longitudinally of the sole resting thereon, heel flap splitting means, adhesive applying means, and a buffing roller, all mounted upon the reciprocable frame, the roller being pivotally supported on the frame and acting on the sole during the travel of the frame in both directions, and cam means for preventing contact of the roller with the forepart of the sole.

12. A machine of the class described comprising a table on which the sole to be treated rests, a frame reciprocable over said table longitudinally of the sole resting thereon, a heel flap splitting and adhesive applying unit, and a buffing roller, said unit and roller being carried by said frame and acting on the sole during the travel of the frame in both directions, and means for preventing contact of the roller with the forepart of the sole, which means comprise a bar mounted on the table and projecting upwardly therefrom parallel to the forepart of the sole, and a freely rotatable roll carried by the roller mounting, which roll rides on the bar to raise the roller away from the table.

13. A machine of the class described comprising a table on which the sole to be treated rests, a frame reciprocable over said table longitudinally of the sole resting thereon, a heel flap splitting and adhesive applying unit, and a buffing roller, said unit and roller being carried by said frame and acting on the sole during the travel of the frame in both directions, said unit including a heel flap splitting blade having a plurality of openings therein behind the cutting edge thereof, a plurality of plungers which enter said openings, a passage normally filled with adhesive, said plungers having passages therein which lead to the lower ends thereof, and which are normally out of register with said adhesive filled passages, and means for advancing said plungers in the blade openings to bring the passages in the plungers into register with the adhesive filled passage, said plunger advancing means being actuated during the retraction of the frame to supply adhesive to the split sole.

14. A machine of the class described comprising a table on which the sole to be treated rests, a frame reciprocable over said table longitudinally of the sole resting thereon, a heel flap splitting and adhesive applying unit, and a buffing roller, said unit and roller being carried by said frame and acting on the sole during the travel of the frame in both directions, said unit including a crossbar, a heel flap splitting blade secured to the under side of the crossbar which acts during the advance of the frame, the crossbar having pockets therein which register with openings in the blade behind the cutting edge thereof, plungers in the pockets and openings, which plungers have passages therein through which adhesive is supplied to the split sole during the retraction of the frame.

15. A machine of the class described comprising a table on which a pair of soles to be treated

rest, a frame reciprocable over said table longitudinally of the soles resting thereon, heel flap splitting, adhesive applying and buffing instrumentalities carried by the frame, a partition strip

5 extending longitudinally of the table between the soles, means for positively raising the strip, and means for actuating said raising means to release the strip at the beginning of the travel of the frame and to raise said strip at the end of such travel.

10 16. A machine of the class described comprising a table on which a pair of soles to be treated rest, a frame reciprocable over said table longitudinally of the soles resting thereon, heel flap splitting, adhesive applying and buffing instrumentalities carried by the frame, teeth on said table upon which said soles are imbedded during the travel of the frame, means for disengaging said soles from the teeth at the completion of the travel of the frame, and means for ejecting said disengaged soles from the machine.

15 17. In a machine of the class described, a blade by which a flap is split from the heel of the sole, said flap remaining connected at its forepart to the sole and being raised from the heel by the 25 knife, means for applying adhesive to the surface of the sole from which the flap has been split and raised, and a buffing roller operative to press the flap down upon the adhesive treated surface while concomitantly buffing the exposed surface of the flap, a table on which said sole rests during such treatment, and a frame reciprocable over the table, on which frame said blade, adhesive applying means and said flap pressing means are 30 mounted, whereby the operations on the sole are performed during the reciprocation of the frame.

18. In a sole treating machine of the class described a work supporting table, a table having a longitudinally extending slot substantially midway between its lateral edges, a sole locating partition disposed in said slot, sole buffering means, means for moving the table and the sole buffering means relatively, longitudinally of a sole resting on the table, means operative to hold the sole locating partition in elevated position thereby to position a pair of soles upon the table with their longitudinal axes substantially parallel, and means operative to lower the sole locating partition before the buffering means actually contacts the soles.

50 19. In a sole treating machine of the class described a substantially horizontal work supporting table, means supporting the table for vertical movement to an extent approximating the thickness of a sole, the table having a longitudinally extending slot, a sole locating partition disposed in said slot, said partition being operative at times to separate two soles resting upon the table, an ejector operative to discharge soles longitudinally from the table, longitudinally slidably cam bars beneath the table each bar having cam surfaces, means cooperable with the cam surfaces of the respective bars for elevating the table and the partition respectively, a transversely extending cam shaft, cams on said shaft operative to move the cam bars longitudinally in one direction and also to actuate the ejector, respectively, and spring means operative to restore the cam bars and the ejector to their initial positions.

60 20. A machine of the class described comprising a table on which the sole to be treated rests, a frame reciprocable over the table lengthwise of the sole resting on the table, heel-flap splitting means and a positively rotated buffering roll both mounted on the frame, said roll being so

supported and arranged as to tend to move downwardly into contact with a sole resting on the table, the splitting means and roll being so relatively located on the frame that the roll contacts the sole in advance of the splitting means during forward travel of the frame, the roll operatively engaging the heel portion of the sole as the frame travels in both directions, and means including a cam element constructed and arranged to raise the roll completely out of operative contact with the sole as the roll reaches the forward end of the heel portion of the sole during the forward stroke of the frame and to maintain it in such raised inoperative position during the return stroke of the frame until the roll nears the forward portion of the heel, and means for reciprocating the frame relatively to the table.

21. Method of preparing a sole comprising the steps of preliminarily buffing the heel portion of the sole beginning at the rear end of the sole, commencing the splitting of a flap of desired length and thickness from the grain side of the rear portion of the sole before the preliminary buffing operation is complete, completing said splitting without detaching the forward end of the flap from the sole, applying a coating of adhesive to a portion, at least, of the surface of that part of the body of the sole from which the flap was split, laying the flap back against the adhesively coated area, and while pressing the flap into adhesive engagement with the body of the sole concomitantly completing the buffing of the rear portion of the sole.

22. Method of preparing a sole comprising preliminarily buffing the rear portion of the sole beginning at its rear end and progressively forwardly, splitting a grain flap from said rear portion, the splitting being commenced before the preliminary buffing is completed, applying adhesive to the split area of the rear portion of the sole while holding the flap away from the body of the sole, and simultaneously pressing the flap back against

the body of the sole so as to cause it to adhere to the latter while completing the buffing of the grain surface of the flap.

23. That method of preparing a shoe sole which comprises as steps buffing the rear portion of the sole beginning at its rear end and progressing forwardly, progressively splitting a flap of predetermined length and thickness from the rear portion of the sole, the splitting operation commencing before the preliminary buffing operation is complete, coating the exposed surface of the body of the sole from which the flap was split with adhesive, laying the flap back against the adhesively coated surface of the body of the sole, and while completing the buffing operation pressing the flap against the adhesively coated body of the sole by the action of the buffing means.

24. Method of preparing a sole, comprising the steps of preliminarily buffing a portion of the grain surface of the sole beginning at its rear end and progressing forwardly, splitting a flap from the buffed portion of the sole, and temporarily reuniting the flap to the surface of the sole from which it was split while at the same time completing the buffing of the grain surface of the flap.

25. Method of preparing a sole, comprising the steps of preliminarily buffing the rear portion of the sole, splitting a flap of desired length and thickness from the grain side of the rear portion of the sole without detaching the forward end of the flap from the sole, the splitting operation being commenced before the preliminary buffing operation is finished, coating two parallel spaced strips of the exposed surface of the body of the sole from which the flap was split with adhesive, said strips extending longitudinally of the sole and each strip being spaced inwardly from an edge of the sole, laying the flap back against the adhesively coated areas, and while pressing the flap against said adhesively coated areas completing the buffing of the grain surface of the flap.

JACOB S. KAMBORIAN.
